UNITED STATES PATENT OFFICE.

JAMES WILKINSON, OF BIRMINGHAM, ALABAMA.

ELASTIC-FLUID TURBINE.

SPECIFICATION forming part of Letters Patent No. 739,965, dated September 29, 1903.

Application filed June 16, 1903. Serial No. 161,708. (No model.)

To all whom it may concern:

Be it known that I, JAMES WILKINSON, a citizen of the United States, residing at Birmingham, in the county of Jefferson and State of Alabama, have invented certain new and useful Improvements in Elastic-Fluid Turbines, of which the following is a specification.

My invention relates to improvements in elastic-fluid turbines wherein fluid-pressure is converted by stages into velocity or vis viva, which is transformed into mechanical power by being directed against successive rows of revolving vanes peripherally mounted on rotor-wheels.

According to my invention a plurality of separate compartments are formed within the casing of the turbine by diaphragm-partitions provided with central openings encircling the main shaft, upon which are mounted a series of rotor-wheels, one of which revolves within each separate compartment. Nozzles are disposed around the several diaphragms, so that they deliver the fluid stream successively to the vanes carried by the rotor-wheels, and with the vanes form working passages, which enlarge in the direction of the flow of the fluid to accommodate the increasing volume of the stream as its pressure is converted into velocity and fractionally abstracted.

This step-by-step or stage expansion of the fluid-pressure, whether effected in a compound turbine, as above described, or in a plurality of separate casings between which the nozzles are formed as conduits, requires as an essential prerequisite that the pressure maintained in the several compartments should be constant; otherwise the turbine parts will be thrown out of proportion to the pressure and a material loss of efficiency will result throughout the stages. For this reason each of the rows of nozzles should exhaust into a chamber having a calculated pressure, which should be the same as the pressure of efflux of the fluid stream to enable the latter to exert its influence at the highest efficiency upon the vanes, for if the chamber pressure be less than that of the fluid efflux, the streams will expand farther in all directions upon their exit from the nozzles and, becoming ungovernable, will lose in efficiency; but if the chamber-pressure be greater a heterogeneous motion will be set

up in the nozzle, which will retard the velocity or vis viva developed therein. It is also true that if the predetermined pressures of the several stages vary there will be a corresponding variation in the volume of the fluid streams, which will defeat the proportions which should be maintained for a constant speed of rotation between the relatively increasing volume of the streams and the correspondingly-enlarged nozzle-passages. This variation in the stage pressure is principally caused by the uncertain element of leakage. It is therefore of prime importance to the successful operation of a turbine adapted to expand the pressure in stages and fractionally abstract its vis viva, either in a series of separate simple turbines or in a compound turbine, wherein the stages are in reality complete simple turbines within one shell, that there should be no leakage of the fluid between the wheel-chambers that cannot be accurately calculated, and for the sake of economy there should be none at all. The most serious difficulty encountered in controlling or stopping this leakage arises from the great speed attained by the revolving parts of the turbine and their angular adjustment or vibratory play relative to the stationary parts, which renders any positive packing both impracticable and dangerous. The floating packing rings or washers heretofore used are subjected to great friction because, being forced against their seats by the full difference in pressures between which they operate, they make no provision for the transverse and angular variations of the shaft by which they are continually shifted. The ideal packing must be one which leaves ample clearance around the shaft and at the same time is capable of adapting itself to any and all variations of the rotating parts, whether transversely, vertically, or angularly.

According to my invention I meet these requirements by interposing annular pressure-reducing valves at the points of leakage around the shaft between compartments or in the stuffing-boxes and so construct them that the difference between the pressures on either side of the valves is utilized to automatically suspend them out of frictional engagement with or to regulate their approximation to the revolving disks or wheels that form their seats,

with a view to controlling the leakage at these points. Within this valve in the clearance-space between it and the revolving parts a pressure of equilibrium is maintained by the regulated leakage from the higher to the lower pressure, which is intermediate the two pressures and which suspends the valve so that it acts with a wiredrawing action against its high-pressure seat to control the leakage.

10 The valve is made free to rock or move longitudinally of the turbine, and since it leaves ample clearance around the shaft it readily and automatically adjusts itself to all variations of the rotating parts, and at the same time will so control the leakage that the compartment or stage pressures may be accurately calculated. Having by these means reduced the heretofore-variable leakage between stages to a point where it can be readily calculated,

15 it is necessary to so construct the nozzles that they will effect the desired drop in pressure at each stage. This drop will be proportioned to the number of stages, ranging from ninety pounds in a single-stage turbine to twenty pounds in a five-stage turbine, considering the boiler-pressure at one hundred pounds. In the former instance the nozzle must convert ninety per cent. of the pressure into velocity, while in the latter the succeeding nozzles must convert, respectively, twenty percent., twenty-five percent., thirty-three percent., fifty percent., and ninety percent., of the stage pressures into velocities. When the drop is below about forty-two per cent. of the pressure, I use nozzles of the converging or straight types, wherein the fluid in passing therethrough expands only in the lineal direction of its flow, but when more than this percentage is to be transformed into velocity I use

20 nozzles of the De Laval type, wherein the fluid expands both lineally and laterally. Thus according to my invention in a compound turbine or series of simple turbines the first row or rows of nozzles may be converging, the intermediate straight, and the last expanding, which arrangement is of material importance to the successful operation of stage expansion-turbines, for if expanding nozzles were used in the earlier stages the fluid

25 would be expanded below the pressure of the receiving chamber, which would result in the development of heterogeneous motion in the fluid stream before the point of efflux, or if a straight nozzle were used at the final stage it would not convert all of the pressure into velocity, but would permit a portion of it to escape through the vanes into the exhaust.

30 It is a further object of my invention to provide valves in the several nozzles and to so connect them up in the direction of the flow of the fluid across the several stages that the corresponding valves in each set are simultaneously operated and the turbine regulated uniformly throughout the several stages and its power varied according to the load without altering the relative volume of the elastic fluid delivered to the several compartments.

My invention consists in the construction and arrangement of parts hereinafter described, and more particularly pointed out in the claims, reference being had to the accompanying drawings, which form a part hereof, and in which—

Figure 1 is a sectional view of the turbine, taken through the central line of two sets of oppositely-disposed fluid-passages provided with valves and linked operating-gear therefor. Fig. 2 is a side view partly broken away to show in section the nozzles, valves, and rotating vanes of a three-stage turbine, with a modified form of valve - operating gear. Fig. 3 is a broken - away sectional elevation corresponding to that of Fig. 2, and showing a three - stage turbine in which the valves are omitted, the nozzles of the upper rows being of the straight type with parallel sides, while the lower nozzles are of the expansion type, which increase in cross - sectional area toward their discharge ends. Fig. 4 is a similar view of a four-stage turbine wherein the nozzles are all of the straight type. Fig. 5 is an enlarged view showing the annular valve and the manner of mounting it within the diaphragms between the rotor - wheels. Figs. 6 and 7 are detail views of the valve. Figs. 8, 9, 10, and 11 show modifications of the valve and illustrate the principle of its action. Figs. 12 and 13 are detail views of the packing-ring for the valve. Fig. 14 is a plan view of one of the diaphragm - partitions, a vertical section of which is shown in Fig. 15, with views of its several parts in Figs. 16, 17, 18, and 19.

Similar reference - numerals refer to the same parts throughout.

According to my invention as applied to a compound turbine the casing is provided with a number of transversely-arranged diaphragm - partitions 1, that divide its interior into transverse chambers through which the turbine - shaft 2 extends, with ample clearance between itself and the centrally - disposed openings in the partitions within which it revolves. These chambers constitute wheel - compartments, and within each of them revolves a rotor - wheel 3, keyed to the shaft and provided with a ring of concavo-convex vanes or blades 4 around its circumference.

The fluid enters the turbine through the circular passage 5 in the head of the casing 6 and is directed by a series of nozzle - passages 7, formed by a series of inclined partitions, against the revolving vanes in the first compartment. After passing through the nozzles 7 and impinging upon the first ring 120 of vanes 4 the fluid - pressure reaches the second chamber through a similar series of nozzle - passages formed in the diaphragm - partitions around their outer peripheries, and arranged to direct the streams of fluid - pressure against the ring of vanes revolving in the second chamber, and so on through the series of wheel - compartments and nozzle - passages until the fluid is delivered by the last

wheel to the circular exhaust-passage 8 in the head 9, from which it may be discharged through outlet 10 into the atmosphere or a condenser. Each of the nozzles 7 has a well-rounded entrance to keep their capacity efficiency high, and when it is desired to regulate the turbine according to varying loads I provide a separate valve 11, located within and when open forming a part of the rounded entrance or throat of each nozzle. These valves are preferably cylindrical and have a centrally and longitudinally disposed fluid-passage formed with rounded sides 12, which constitute a part of the nozzle-throat when admitting fluid.

The diaphragm-partitions 1 are preferably dished against the pressure to increase their strength to withstand heavy strains and have circumferential shoulders 13 and flanges 14, which constitute the sides of the turbine-casing. The nozzle-passages 7 pass at an incline through the shoulder 13, and seats for the cylindrical valves are bored therein radially from the outside. Into the entrances of these rounded valve-openings, which are threaded, are secured the packing-glands 15, through which the stems 16 of these valves pass. Cranks 17 on these stems are linked together in series from one row to another in the direction of the flow of the fluid by links 18, so that in varying the power of the turbine according to changing loads the same number of nozzles will be thrown on or off throughout the stages, and it will be noted that by operating these valves in the direction of the travel of the fluid the streams delivered by those nozzles of the first row which are open will not be deflected from a substantially straight course to the exhaust by reason of those nozzles in the succeeding stages in the line of the streams' flow being closed, as might readily occur if the valves were linked together in vertical rows.

For operating the valves a crank or handle 19 may be mounted directly on a valve-stem or, as shown in Fig. 2, on a separate spindle 20 when a short crank 21 thereon is connected by a link 22 with the links 18, through which the several valve-cranks are operated. It will be noted that the spindle 20 is not in alinement with the valve-stems, but is so disposed relatively to cranks 17 that when the valves are closed the links 18 and 22 will be in alinement with crank 21, which latter will be on the "dead-center," as it were. This has the effect of retarding the movement of the valves as the crank approaches this point—*i. e.*, when the valves are closing. At the same time it will increase the leverage exerted upon the cranks 17 to open the valves when this is most needed. Though, as shown, the valves are hand operated, I intend controlling them singly or in groups by an automatic governing mechanism, such as is described in an application filed by me on April 7, 1903, Serial No. 151,504.

If a proper fluid-pressure be supplied to the

passage 5, the active nozzles 7, after transforming a portion of the fluid's energy of pressure into energy of velocity, will deliver it in streams against the first row of revolving vanes 4, causing them to rapidly rotate. As the fluid is delivered to the succeeding rows of nozzles, which increase in area to a calculated extent, fractions of its total pressure will be converted into velocity at each stage. This velocity, which is due to the drop in pressure, will be totally absorbed by the moving vanes, so that they deliver to the succeeding row of nozzles only the remaining energy of pressure in the fluid, except at the last stages, when the vanes may be lengthened out and the pressure of the exhaust so reduced that the fluid after delivering its energy of impact to the vanes will exert against them also its energy of reaction in expanding outwardly from between them. In a cycle of action of this kind, whether carried on within a single compound casing or a series of separate casings, it becomes of maximum importance to reduce the leakage of fluid-pressure from the wheel-compartments not only with a view to economy, but because the turbine parts will be thrown out of proportion to the pressure and its efficiency affected, unless the calculated pressure at each stage should remain constant. With this object in view I interpose in the stuffing-boxes 23 and 24 of the turbine-casing and in the central openings in the diaphragms of a compound turbine an annular pressure-reducing valve 25, which surrounds the shaft and is adapted to move longitudinally of itself between collars or disks 26 in the stuffing-boxes and wheels 3 in the turbine-casing, which serve as its seats. Referring now to the valves in the turbine, I seat them pressure-tight within the flanged central openings in the diaphragms, wherein is provided a circular groove or channel 27, in which is seated a packing-ring 28. This ring engages the outer periphery of the valve 25, clasping it so as to make a pressure-tight connection therewith while permitting of its longitudinal adjustment. It is not intended that the valve 25 should rotate, and it may therefore have a vertically-disposed slot 29, corresponding in length with the valve's play, which is engaged by a lug or projection 30; but the valve may be permitted to rotate slowly, following the rotation of its seats. The ring 28 is preferably of an integral spring-piece and may have its lower face—*i. e.*, the face toward the low pressure—curved so as to form a rocking or ball-joint seat with the correspondingly-curved lower face of the groove 27, as shown more clearly in Fig. 10. The springs 31 (shown in this figure) may be used, if desired, to take up the shifting movements of the valve and ring. When the ball-faced joint is used with the ring, the valve does not seat flush against the inner convex walls of the flanged diaphragm-opening, but is slightly clear of it, which permits of the valve assuming larger angular variations to

compensate all ordinary changes of the relative positions of the rotating to the stationary parts caused by differences in expansion, contraction, deflection, wear, or defective adjustment. As shown in Fig. 11, a plurality of packing-rings may be used.

Though the hubs of the wheels 3 are shown entirely incasing the shaft, I may further reduce the leakage by so spacing them apart or dispensing with their hub-flanges that the valves may be adapted to encircle the shaft directly. This arrangement, while not so simple as that shown, would have the advantage of reducing the circumferential area of leakage between compartments.

The stuffing-boxes 23 and 24 are provided with annular partitions or flanges 32, having grooves, packing-rings, and valves, as in the turbine, with the exception that the valves will be reversed to head toward the high pressure in the casing. The disks or collars 26 correspond to the rotor-wheels in that they form the revolving seats for these valves, any desired number of which may be used. In the stuffing-box 24 the collar has a flange 33, which dips into a water-receptacle 34, forming a water-seal valve to prevent air entering the turbine when operated by steam and run condensing. Water is admitted through an opening 35 and discharged through an outlet 36.

The valves 25, which I use to control the leakage of pressure, are annular rings, either integral or in sections bolted together, which have circular longitudinally-extending flanges 37, disposed around the upper or high-pressure end of the valves, and flaring outwardly-disposed flanges 38, having a circumferential lip 39 on the low-pressure ends. For convenience in describing the action of the valve as applied to a compound turbine the pressure in the first wheel-compartment will be represented by A, that in the second by B, &c., and it will here be noted that the pressure of the whole compartment being the same it will be equal on both sides of each wheel and the end thrust will thus be reduced to a minimum.

When the turbine is in action, the pressure in the discharging-compartment will be in excess of B in the receiving-compartment, which difference of pressure I use in connection with the valves 25 to create a third pressure within said valves, which I term the "pressure of equilibrium." This pressure is maintained within the annular space or clearance between the valve and the shaft or the flanged hubs of the wheels which inclose the shaft, and this space may be enlarged for the purpose of increasing the area of this pressure and making its effect on the valve more positive by forming a chamber in the inner periphery of said valve, as in Fig. 10, and undercutting the flange 38 from the lip 39 inwardly to form a continuance of said chamber. Taking, for example, the valve in Fig. 5, the upper wheel forms its high-pressure

seat, between which and the flange 37 is the circular variable opening a, leading from the high-pressure compartment into the valve-chamber, while the lower wheel forms its low-pressure seat, with an opening b between it and the lip 39, communicating with the low-pressure compartment, and it is my intention to so shape the valve that, sensitive to the different pressures between which it acts, it will automatically adjust itself to its seats, so as to regulate the openings a and b, with a view to controlling and maintaining the pressure of equilibrium, which is intermediate the pressures above and below the valve.

According to Fig. 8, where an annular valve of the plain type is shown, this pressure of equilibrium cannot exist, because the pressure A, passing the opening a, presses the valve down with a pressure per square inch equal to the difference between the pressures A and B, and though there will be a pressure within the valve it will remain wholly in one direction, since the valve is rectangular in cross-section and can have no lifting effect on the valve to counteract the downward thrust of the pressure A, which presses it hard against the face of the lower wheel. This will stop all leakage; but the speed of rotation of the wheels in these turbines is so great that such a bearing would be impractical on account of friction. Therefore according to my preferred form I make provision for a small leakage to occur at this valve, which I utilize for several purposes, of which the most important is the maintenance of the pressure of equilibrium. Referring now to Fig. 9, it will be seen that the pressure A enters the valve-chamber through a and passing under the valve's flange 38 counteracts or equalizes the valve's end thrust; but the lip 39 will still be pressed against the lower wheel by the pressure B on top of the projecting flange 38. This difficulty is positively removed by extending this flange, as shown in Figs. 5, 10, and 11, for we now have the pressure A passing around the valve and under the flange, and when it exceeds in the recessed area under the flange the pressure of B upon the flange in addition to the weight of the valve the latter will rise. When this occurs, the flange 37 approaches the upper wheel, wiredrawing the opening a and reducing the pressure A entering the valve-chamber from the high-pressure compartment, while simultaneously the opening b is effected and pressure escapes from the valve-chamber into the pressure B in the low-pressure chamber. This occurs until a pressure of equilibrium is reached in the valve-chamber, when the valve remains at rest, and the pressure is maintained by the gradual leakage around the valve. This small leak is not only of such a character that it can be readily calculated, but it also serves the purpose of lubrication by maintaining a thin film of lubricated steam or other elastic fluid passing between the flanges 37 39 and their ro-

tating seats. It also prevents the accumulation of water, which would cause great friction between the stationary and rapidly-rotating parts. Thus instead of endeavoring 5 to stop the leakage entirely it is my intention to control or regulate it within limits, so that it may be calculated and provided for in the turbine construction.

The quantity of elastic fluid required to 10 maintain this equilibrium pressure being determined, partly by the area of the flange 38, the area of the opening b , and the difference in pressures above and below the valve, it is evident that the parts may be so designed that 15 the valve will touch the upper wheel with any desired degree of pressure less than the difference between the pressures A and B. In the same manner this pressure can be so adjusted that the frictional heat caused by the 20 contact of the two surfaces will not be so great that it cannot be readily conducted away through the fluid and the mechanism.

The valve may also be caused to suspend 25 itself in equilibrium between the moving wheels or disks without having contact with either or to approach the upper as closely as may be desired and operate thus with a thin annular film of lubricated fluid separating it from the wheel-face. The thickness of this 30 film may be regulated so that only enough fluid to keep its faces 37 and 39 lubricated and to cause sufficient circulation to prevent condensation within the turbine will be allowed to pass.

35 As applied to a stage-expansion turbine comprising a series of simple turbines in separate casings, my improved valves will be located in the stuffing-boxes of the several casings, which boxes may be common to adjoining 40 casings, to which the fluid is successively conducted through conduits.

Having removed the uncertain and variable factor of leakage between compartments, it is with some precision that the drop in pressure 45 between them can be provided for in shaping the nozzles or passages for the fluid that actuates the wheels. These passages may be in the form of straight nozzles with parallel sides, or they may converge toward 50 their discharge ends, or they may be of the expansion type, diverging toward their discharge ends; but whatever the shape used they will have rounded entrances to keep their capacity efficiency high. They may be used 55 with or without valves, and where valves are used they will be shaped to form the rounded entrances to the passages when open.

The passages will be designed with a view to keeping the proper pressure constantly the 60 same at the different stages during the turbine action, and they will be required to transform to velocity only such portion of the pressure as will be absorbed by the first succeeding row of vanes. The type of the nozzle 65 to be used depends on the percentage of the stage pressure which it must convert into velocity, and this is determined by compar-

ing the total pressure of the discharging with that of the receiving compartment. Thus if the discharge-compartment has a pressure of one hundred pounds per square inch and the receiving-compartment eighty pounds there will be a twenty-per-cent. drop, in which case I will use either the straight or the converging nozzle, according to the shape of the receiving buckets or vanes, and with either of these nozzles I can obtain all the velocity due to the twenty-per-cent. drop in pressure. Also by maintaining the receiving-compartment's pressure at eighty pounds, which is the pressure of efflux of the nozzle, the stream will have no tendency to further expand after delivery from the nozzle, making its energy easy to transform into motion in the vanes. In cases when the drop is greater than forty- 75 two per cent. of the pressure in the discharging-compartment I will form the nozzles to diverge toward their discharge ends and at a ratio slightly less than that of the increase in the volume of the fluid due to its fall in 80 pressure, so that all the energy of the pressure thus transformed may be converted into velocity, and there will thus be no further expansion of the fluid after it leaves the nozzle. In places where the final pressure is 85 high I may use the straight nozzle for injecting the fluid into the last row of vanes, and in such cases where the drop is greater than forty-two per cent. I will shape the vanes to form a series of deep receptacles, so that they 90 will absorb all the velocity of impact and in discharging the remaining pressure will absorb therefrom the energy of its lineal reaction.

Obviously the application of my pressure-reducing valve to control the leakage between different pressures, whether atmospheric or otherwise, makes its field of usefulness independent of any specific form of turbine, though in the application shown the construction and control of the fluid-passages are especially adapted to coöperate with the valve in maintaining constant the stage pressures.

By the expression "compartment" I mean a chamber within which a wheel rotates, 115 whether it be separate from or combined with similar chambers in the same or different casings.

Having thus described my invention, what I claim as new, and desire to secure by Letters 120 Patent, is—

1. In an elastic-fluid turbine, the combination with rotating elements, of two or more separate compartments inclosing said elements, and intermediate stationary passages 125 between said compartments to which they deliver the fluid in succession, and automatic means to regulate the leakage from said compartments.

2. In a compound elastic-fluid turbine having one or more diaphragm-partitions and a main shaft, the combination of floating rings, seated fluid tight in said diaphragms and leaving a clearance around the shaft, with ro-

tating elements which form seats for said rings and between which they are automatically adjustable.

3. In a compound elastic-fluid turbine having a plurality of diaphragm-partitions forming separate wheel-compartments, the combination with a plurality of wheels intermediate the partitions, of means carried by said partitions and automatically adjustable between said wheels' revolving surfaces to control the leakage between compartments.

4. In an elastic-fluid turbine operating by stage expansion, a series of separate compartments within which different pressures are maintained, of an automatic pressure-reducing valve to govern the leakage between compartments.

5. In an elastic-fluid turbine operating by stage expansion, a plurality of separate wheel-compartments, a shaft, wheels thereon which revolve within said compartments, and means, automatically sensitive to the difference in pressures between the compartments, which maintain between the partitions and the shaft pressures intermediate those of the communicating compartments which control said means.

6. In an elastic-fluid turbine, a valve placed at a point of leakage between different pressures whether atmospheric or otherwise, a seat therefor, the said valve being adapted to maintain within itself a pressure intermediate those between which it operates, and to be actuated and controlled by said intermediate pressure to regulate the leakage at that point.

7. In a compound elastic-fluid turbine operating by stage expansion, a series of partitions forming compartments wherein different pressures are maintained, and a series of movable rings which automatically maintain between said compartments a series of intermediate pressures.

8. In an elastic-fluid turbine, a flanged ring-valve adapted to act at a point of leakage near the shaft between different pressures, said valve having a transverse flange in its low-pressure end, and a seat therefor, between which and said flange the higher pressure has access to automatically actuate the valve.

9. In an elastic-fluid turbine, a ring-valve adapted to act at a point of leakage between compartments wherein different pressures are maintained, a seat for said valve in each compartment, a flange on said valve disposed within each compartment which are acted on by the different pressures and proportioned to control the pressure-reducing action of the valve.

10. In a turbine of the class described, a plurality of wheel-compartments having different pressures, wheels, annular rings interposed between compartments, said rings having outwardly-projecting flanges around their low-pressure ends and a flange around their high-pressure end, and means to sup-

port said ring-pressure tight while permitting of its endwise adjustment between the faces of the wheels which form its seats.

11. In a turbine of the class described, rings loosely surrounding the shaft and placed at points of leakage between different pressures, whether atmospheric or otherwise, revolving disks carried by said shaft between which said rings are adjustably suspended, said rings being sensitive to the difference of the pressures between which they operate and so proportioned relative thereto that they are automatically maintained in a position relative to said disks to govern the said leakage.

12. In an elastic-fluid turbine, stationary diaphragm - partitions forming wheel - compartments wherein different fluid - pressures are maintained, a shaft, rotor-wheels thereon having concavo-convex vanes, and a movable annular flanged packing-ring between compartments which leaves a clearance around said shaft.

13. In a turbine of the class described having wheel - compartments wherein different fluid-pressures are maintained, a shaft, rotor-wheels thereon, an annular packing-ring between compartments adapted to act as a pressure - reducing valve and maintain in its interior a third pressure, which third pressure is different from the compartment pressures and suspends said valve between its moving seats.

14. In a turbine of the class described having separate compartments wherein different pressures are maintained, rotating elements therein, nozzle-passages connecting said compartments, and annular valves between compartments and sensitive to the differences in pressures therein by which they are automatically held to their seats with a pressure less than said differential between which they operate.

15. In an elastic-fluid turbine, an annular valve adapted to act at a point of leakage around the shaft between different pressures, a stationary support for said valve, a ball-faced groove in said support, a packing-ring around said valve having a ball-faced bearing end seated in said groove.

16. In an elastic-fluid turbine acting to expand the fluid-pressure in stages, stationary partitions forming compartments and rotating elements therein, in combination with means for maintaining predetermined pressures in the several compartments comprising fluid-passages in said partitions, separate valves in each passage, and means to automatically regulate the leakage of pressure between compartments.

17. In an elastic-fluid turbine operating by stage expansion, a series of wheel-compartments, wheels therein, nozzle-passages between compartments designed to convert equal quantities of the total pressure into velocity at each stage, and means co-operating therewith to maintain the pressure in each compartment equal to the pressure of the

fluid-stream delivered thereto by regulating the leakage between compartments.

18. In an elastic-fluid turbine of the class described, circular rows of fluid-passages alternating with rows of revolving vanes, valves in said passages, operating-stems for said valves, links connecting said stems across the rows and an operating-lever connected to said links and in alinement therewith when the valves are closed.

19. In an elastic-fluid turbine operating by stage expansion, a series of wheel-compartments, wheels having peripheral vanes revolving in said compartments, nozzle-passages between said compartments which direct the fluid-streams against said vanes, valves controlling the admission of pressure to said nozzles, means to simultaneously open or close the same number of valves in each succeeding row of nozzles, and automatic means to govern the leakage between compartments.

20. In an elastic-fluid turbine, a series of diaphragm-partitions dividing it into several compartments, wheels having peripheral vanes revolving in said compartments, nozzles in said partitions which effect a predetermined reduction in the pressure of the elastic fluid which is absorbed by a succeeding row of vanes to which it is delivered, valves in said nozzles, and automatic means to regulate the leakage between compartments.

21. In an elastic-fluid turbine wherein pres-

sure is reduced in stages and directed by successive nozzle-passages against intermediate rows of vanes, a plurality of rows of nozzles, part of which expand the fluid pressure only linearly, while the other rows expand it both linearly and laterally.

22. In an elastic-fluid turbine operating by stage expansion a series of revolving elements and intermediate stationary rows of nozzle-passages having rounded entrances, the first row or rows of said passages in the direction of the flow of the fluid being of the parallel type and the latter row or rows being of the expansion type.

23. In an elastic-fluid turbine wherein the pressure is reduced in stages, a series of wheel-compartments which constitute different stages, a rotating element in each compartment, nozzle-passages between said compartments which are inclined and arranged to succeed each other in the direction of the flow of the fluid, valves for said nozzles which when open form the rounded entrances to said nozzles, stems for said valves which project radially from the casing, cranks on said stems, and links connecting said cranks together in the line of the fluid's flow.

In testimony whereof I affix my signature in presence of two witnesses.

JAMES WILKINSON.
